UNITED STATES PATENT OFFICE.

JOSEPH S. DUNCAN AND HENRY E. HUBBARD, OF CHICAGO, ILLINOIS, ASSIGNORS TO
ADDRESSOGRAPH COMPANY, OF CHICAGO, ILLINOIS, A CORPORATION OF ILLI-
NOIS.

LISTER ATTACHMENT FOR ADDRESSING MACHINES.

Application filed June 23, 1919. Serial No. 306,010.

To all whom it may concern:

Be it known that we, JOSEPH S. DUNCAN and HENRY E. HUBBARD, citizens of the United States, residing at Chicago, in the 5 county of Cook and State of Illinois, have invented certain new and useful Improvements in Lister Attachments for Addressing Machines, of which the following is a specification.

10 The object of this invention is to provide an attachment for addressing machines whereby the names or the full addresses may be printed in a list form on ruled or plain sheets. The invention is especially useful 15 in preparing pay-rolls, stockholders' lists, factory records, subscription records and for a great many other purposes where a list of names is desired in alphabetical or other arrangement on loose leaf or other sheets.

20 The invention also has for its objects to provide a lister attachment which can be easily affixed to and removed from an addressing machine, which can be easily thrown into or out of operation, and which 25 can be readily adjusted for properly feeding the sheet through the machine according to any desired spacing.

Another important object of the invention is to insure proper spacing and feeding of 30 the sheet by avoiding slippage at the beginning of the feeding movement and any tendency of the sheet to over-run the desired spacing due to momentum of the sheet and the feeding devices at the finish of the feeding movement.

Other objects of the invention are to provide an attachment of simple construction which requires no special skill to operate, which can be operated by hand for skip 40 spacing or other purposes, which can be thrown out of operation temporarily in a very simple manner and which is capable of fine and accurate adjustment for spacing.

In the accompanying drawings we have 45 shown the invention embodied in a hand addressing machine of that type in which the addressing devices are automatically fed one at a time through printing position and discharged at the front of the machine, but it 50 will be understood that the invention may be embodied with any addressing machine for which it is or may be adapted.

In the drawings—

Fig. 1 is a perspective view illustrating a

portion of a hand addressing machine with 55 our improved lister attachment thereon;

Fig. 2 is an enlarged side elevation, partly in section, illustrating the attachment and a portion of the addressing machine in the initial position of the parts; 60

Fig. 3 is a view similar to Fig. 2 showing the parts in position when the platen is making an impression;

Fig. 4 is a front elevation of the attachment showing parts of the machine in section; 65

Fig. 5 is a sectional view on the line 5—5 of Fig. 4;

Fig. 6 is a sectional view on the line 6—6 of Fig. 4. 70

Fig. 7 is a sectional view on the line 7—7 of Fig. 6;

Fig. 8 is a side elevation, partly in section, showing the platen in normal position and the feeding devices operated by moving the 75 arm 49 to a position midway between the positions shown in Figs. 2 and 3;

Fig. 9 is a detail sectional view showing the chute in side elevation;

Fig. 10 is a front view and Fig. 11 is a 80 sectional view of the roller ratchet device.

Referring to the drawings, 10 is the bed of the machine and 11 is a magazine to receive a stack of printing devices 12 which are fed through the machine one at a time in a familiar manner. A platen 13 is pivotally mounted at 16 on the bed and is normally held in elevated position by a spring 17, (Fig. 2). An inked ribbon 18 is arranged to travel transversely across the printing device in printing position on the bed and by hand pressure applied to the handle 15 the platen is swung down upon a sheet or envelope 19 to make an impression in a manner now well known in the art. 90

The lister attachment comprises a frame 20 which carries all of the moving parts and is detachably secured to the bed by a single set screw 21. The frame has a pin 22 to enter an opening 22' in the bed for properly 100 centering the attachment on the machine and the screw hole in the bed for the set screw 21 is so arranged that when the attachment is secured in place the working parts will be in proper relation to the working parts of the machine. A feed shaft 23 carrying a feed roller 24 is mounted in the frame 20 and in one arm 25 of a bell crank 26 which is piv- 105

oted at 26' on the frame (Fig. 5). The other arm 25' of the bell crank engages a rock shaft 27 mounted in the frame and cut away at 27' to provide a flat surface in a 5 plane extending through the center of the shaft. A spring 28 housed in the frame bears upon the arm 25 to press the feed roller 24 into operative engagement with the sheet 19 when the arm 25' engages the flat surface 10 27' on the shaft 27. To lift the feed roller out of operative position so that the sheet may be arranged in the machine, or for any other purpose, the shaft 27 is rocked by operating the handle lever 29 (Fig. 4) until the 15 bell crank 26 is swung on its pivot by the peripheral surface of the rock shaft 27 engaging the arm 25'. The drawings show the feed roller in operative position but it will be readily understood that by simply throwing 20 the handle lever 29 upward to rock the shaft 27 the feed roller will be lifted out of feeding position. The shaft 23 is preferably reduced in size between the arm 25 and its bearing in the frame 20 (Fig. 4) so that it 25 will readily yield to permit movement of the feed roller to inoperative position, as just described.

A gear 30 (Fig. 4) is keyed on the shaft 23 and drives a pinion 31 on the shaft 32 30 which is mounted on the frame and carries the feed roller 33 which is located just below and slightly to one side of the axis of the feed roller 24. Thus the feed rollers are geared to revolve together and feed the 35 paper located therebetween.

A gear 34 is loosely mounted on the feed shaft 23 and is engaged therewith by a roller ratchet device 35 or other suitable clutch device which need not be described in detail. 40 A toothed segment 36 (Fig. 2) engages the gear 34 and on its downward movement with the downward movement of the platen the gear turns freely on the shaft but on the upward movement of the platen and the 45 segment the gear is locked to the shaft and turns the shaft and the feed rollers. The segment 36 is carried by a bell crank 37 pivoted at 37' on the frame and is pivotally connected to one end of a link 38 at 38'. 50 The other end of this link is pivotally engaged with a screw 39 (Fig. 6) which screws into an adjusting block 40 in the adjusting head 41. This head is rigidly mounted on a shaft 42 supported in the frame and it 55 has a slotted side 43 (Figs. 2, 3) which is calibrated for adjustment. A plate 44 is mounted on the screw 39 to travel in tracks 43' on the slotted side 43 of the head and this plate is provided with an index mark 60 to register with the calibrations aforesaid.

The block 40 is carried by an adjusting screw 45 which operates through the front of the block and is provided with a cap 46 by means of which the screw can be turned 65 to adjust the block 40 thereon. Since the

screw 39 connects the link 38 with the block 40 the pivot of the forward end of the link will be adjusted with the block relatively to the fixed pivot of the head 41 to regulate the feeding movement of the sheet. The front 70 of the block is calibrated and the cap 46 has an index mark to facilitate adjustment of the screw 45.

The feed shaft 23 may be operated in one direction by turning the knurled finger piece 75 23' but this will be used only for special purposes since the feeding devices are actuated by the platen arm at each complete operation of the platen. An arm 47 on the head (Fig. 1) is pivotally connected by link 48 to 80 a rocker which is operated by the platen arm for actuating the feeding devices. In its approved form this rocker comprises an arm 49 to the upper portion of which the link 48 is pivotally connected. This arm 49 is pivoted at its lower end, 50, to an arm 51 which is pivoted at 52 on the frame 20. The two arms are held spaced apart by the lug 53 on arm 49 engaging the arm 51, and a spring 54 connected to the arms holds them 85 normally in the spaced relation provided for by the lug 53. A roller 55 on the side of the platen arm 14 is arranged to travel in the space between the two arms and to engage arm 49 on the downward travel of the 90 platen to operate the rocker, and to engage the arm 51 on the upward travel of the platen to return the rocker to normal position and to operate the feed rollers. A flat spring 56 fastened to the frame bears upon 95 the arm 51 to relieve the shock of the return movement of the rocker. The arm 49 is provided with a thumb piece 49' at its upper end by which this arm and the feeding devices connected therewith can be operated 100 by hand independently of the platen and platen arm and arm 51 to feed the sheet.

A side gauge 57 for guiding the sheet is carried by a rod 58 which is adjustable in the frame 20 and is secured in adjusted position 105 by the screw 59 (Fig. 1). The sheet is guided upward as it passes from printing position by a chute which consists of a plurality of curved arms 60 connected at their lower ends by a bar 61 and by a cross brace 62. A rearwardly extending projection 63 at one side of the chute engages the frame and a similar projection 64 at the other side of the chute has a reduced end 65 which enters an opening in a lug 66 on the frame in 110 which it is secured by a set screw 67. Thus the chute is secured in proper position on the machine by a single set screw.

The general operation of the machine will be readily understood from the foregoing 115 description when read in connection with the drawings but special mention should be made of the changing speed of operation of the feed rollers. It will, of course, be apparent that the feed rollers operate only 120

on the upward or return stroke of the platen arm, after the printing impression has been made, and that the movement of the mechanism for actuating the feed rollers ends at 5 or about the same time with the return movement of the platen lever. But we desire to commence the sheet feeding movement slowly and also to end it slowly and thereby avoid jerking the sheet, prevent 10 slippage and any overfeed of the sheet which would result from the momentum imparted thereto in the feeding movement. We also wish to speed up the feeding movement between the beginning and ending of the 15 movement. This is accomplished in a very simple manner by the head connection between the rocker and the segment link. It will be noted by reference to Fig. 2 that in the normal position of the machine the head 20 is located with the cap 46 to the front, and, by reference to Fig. 3, that in the down position of the platen the head is turned to reverse position with the cap pointing in the opposite direction. This swinging 25 movement of the head from the position shown in Fig. 2 to the position shown in Fig. 3, and back again, is effected by the rocker and its link connection with the arm 47 on the head. The screw 39 to which the 30 link 38 is connected will travel in an arc determined by the position of the block 40 with relation to the axial center of the shaft 42 and this arc can be varied by adjusting the block as heretofore described. The link 35 38 imparts movement to the segment which turns the feed shaft and the feed rollers thereon on the upward movement of the platen and the segment. Since the screw 39 travels in an arc it will be apparent that 40 the segment, and consequently the feed shaft and feed rollers, will commence and end their movement on the up-stroke of the platen at a comparatively slow rate of speed while the intermediate movement will be 45 at a comparatively high rate of speed. Furthermore, the feeding movement is not commenced until the platen is clear of the work. The extent of the feeding movement can be regulated by adjustments according to any 50 ruling on the sheet or to any desired spacing. If it is desired to feed the sheet in advance without regard to spacing the feed roller can be turned by operating the knurled finger piece 23'. If it is desired to 55 operate the feed rollers according to the adjusted spacing without operating the platen the arm 49 is operated by hand, through the medium of the finger piece 49', and all the feeding devices will be operated 60 except the arm 51 of the rocker. By these means the feeding movement can be adjusted to any desired extent and it can be effected automatically with the operation of the platen or independently thereof as may be 65 desired.

The platen may be constructed and adjusted to take an impression of a part or all of the form on the printing device and for this purpose we may use platens such as are disclosed in Patents No. 1,186,758, June 13, 1916, and No. 1,209,416, December 19, 1916.

We are aware that our invention may be adapted to other kinds of addressing machines than that indicated in the foregoing specification and drawings and also that changes in the form, proportion and construction of parts may be made without departing from the spirit of the invention or sacrificing any of the advantages thereof and we therefore reserve the right to make all such adaptations and changes as fall within the scope of the accompanying claims.

We claim:

1. In an addressing machine, the combination of a platen and means for operating the same, means for feeding a sheet through the machine, and means automatically operated by said platen operating means for actuating said feeding means to advance a sheet through the machine on the return movement of the platen after the printing impression said feeding means being operable independently of said platen. 95

2. In an addressing machine, the combination of a platen and a platen arm, means for feeding a sheet through the machine, and means operated by the platen arm for actuating said feeding means to advance a sheet through the machine on the return movement of the platen after the printing impression, said feeding means being operable independently of said platen arm. 100

3. In an addressing machine, the combination of means for feeding a sheet through the machine and stopping it in printing position, and means for operating said feeding means at a comparatively slow rate of speed at the beginning and at the ending of the feeding movement. 105

4. In an addressing machine, the combination of means for feeding a sheet through the machine and stopping it in printing position, and means for operating said feeding means at a comparatively slow rate of speed at the beginning and at the ending of the feeding movement and at a comparatively high rate of speed during the intermediate part of the feeding movement. 115

5. In an addressing machine, the combination of means for feeding a sheet to printing position including a feed roller, and means for imparting to said roller a feeding movement which begins slowly, then speeds up and ends slowly. 120

6. In an addressing machine, the combination of means for feeding a sheet to printing position including a pair of feed rollers arranged in cooperative relation, and means 130

- for operating said rollers in unison in a feeding movement which begins slowly, then speeds up and ends slowly.
7. In an addressing machine, the combination of means for feeding a sheet to printing position including a pair of rollers arranged one above the other in cooperative relation, shafts carrying said rollers, intermeshing gears on said shafts to turn the rollers in unison, and means for operating one of said shafts to impart a feeding movement to the rollers which begins slowly, then speeds up and ends slowly.
8. In an addressing machine, the combination of a platen and a platen arm, means for feeding a sheet through the machine and including a feed roller, and means operated by the platen arm for actuating said feeding means to impart a feeding movement to said feed roller which begins slowly, then speeds up and ends slowly.
9. In an addressing machine, the combination of means for feeding a sheet through the machine, and means for operating said feeding means including a part which travels in the arc of a circle and in such relation to the center of the arc as to produce a feeding movement which begins slowly, then speeds up and ends slowly.
10. In an addressing machine, the combination of means for feeding a sheet through the machine, means for operating said feeding means including a part which travels in the arc of a circle and in such relation to the center of the arc as to impart to the feeding means a feeding movement which begins slowly, then speeds up and ends slowly, and means for adjusting said part to vary its arc of movement and correspondingly vary the feeding movement.
11. In an addressing machine, the combination of a platen and a platen arm, means for feeding a sheet through the machine, and means actuated by said platen arm for operating said feeding means and including a part for operating said feeding means independently of the operation of the platen arm.
12. In an addressing machine, the combination of a platen and a platen arm, means for feeding a sheet through the machine, and means actuated by said platen arm for operating said feeding means and including a rocker arm operable conjointly with and independently of said platen arm.
13. In an addressing machine, the combination of a platen and a platen arm, means for feeding a sheet through the machine, and means actuated by said platen arm for operating said feeding means and including a rocker comprising two arms, both of which are operable conjointly with the platen arm and one of which is also operable independently of the platen arm.
14. In an addressing machine, the combination of a platen and a platen arm, means for feeding a sheet through the machine, and means actuated by said platen arm for operating said feeding means and including a rocker comprising two pivoted arms yieldingly held in spaced relation, and a roller on the platen arm arranged to travel between said rocker arms to operate the rocker.
15. In an addressing machine, the combination of a platen and a platen arm, means for feeding a sheet through the machine, and means actuated by said platen arm for operating said feeding means and including a rocker comprising two pivoted arms yieldingly held in spaced relation, and a roller on the platen arm arranged to travel between said rocker arms to operate the rocker, said rocker arms being jointly operable conjointly with the platen arm and one of said rocker arms being operable independently of the platen arm.
16. In an addressing machine, the combination of a platen and a platen arm, means for feeding a sheet through the machine, and means actuated by said platen arm for operating said feeding means and including a pivoted rocker comprising a pair of arms, one of which is pivotally mounted on the other and both of which are yieldingly connected, there being a lug on one arm to engage the other arm for holding the arms in spaced relation, and means on the platen arm traveling between said rocker arms for operating the rocker.
17. In an addressing machine, the combination of a roller for feeding a sheet through the machine, a rocker, means for operating said rocker, and means intermediate of the feed roller and the rocker for operating the feed roller and comprising a pivoted head adapted to be operated by the rocker, one side of said head being slotted and provided with a track, a block slidably adjustable in said head in a plane perpendicular to the pivotal axis of the head and relatively to said axis to vary the feeding movement, a plate arranged on said track, and an adjusting screw passing through said plate and engaged with said block.
18. In an addressing machine, the combination of a roller for feeding a sheet through the machine, a rocker, means for operating said rocker, and means intermediate of the feed roller and the rocker for operating the feed roller and comprising a pivoted head adapted to be operated by the rocker, an adjusting screw mounted in said head, and a block adjustably mounted on said screw relative to the pivotal axis of said head.
19. In an addressing machine, the combination of a roller for feeding a sheet through the machine, a rocker, means for operating said rocker, and means intermediate of the feed roller and the rocker for operating the feed roller and comprising a head adapted to be operated by the rocker, a block mount-

- ed in the head to travel in an arc, means for adjusting said arc of travel of the block to regulate the feeding movement, a bell crank lever carrying a segment gear, and a link 5 connected to said lever and to said block.
20. In an addressing machine, the combination of a roller for feeding a sheet through the machine, a rocker, means for operating said rocker, and means intermediate of the 10 feed roller and the rocker for operating the feed roller and comprising a feed roller shaft, a gear on said shaft, a bell crank lever having a toothed segment for operating said gear, a pivotally mounted head adapted to be operated by said rocker, a block adjustably mounted in said head relative to the 15 pivotal axis of the head and moving con-
- jointly with the head but in an arc with relation to said pivotal axis, and a link connected to said bell crank lever and to said block. 20
21. In an addressing machine, the combination of a bed, means for feeding a sheet through the machine, and a chute for guiding the sheet from the feeding means and 25 having a pair of rearwardly extending projections to engage the bed, and a set screw on the bed engaging one of said projections to secure the chute in place on the bed. 25
